Application filed August 25, 1891. Serial No. 404,373. Term of patent 7 years.

To all whom it may concern:

Be it known that I, CORNELIUS BRAUN, a citizen of the United States, residing at Louisville, in the county of Jefferson, State of Kentucky, have invented a certain new and useful Design for a Fire-Place Frame and Summer-Front, of which the following is a specification, reference being had therein to the accompanying drawing.

10 The figure is a face view of my design.

The leading feature of my design consists in a flattened crescent-shaped panel at the top of the front or frame.

15 A are the side panels, which are rectangular in form and ornamented, being capped by the substantially triangular corner-panels B, which may also be ornamented, and across the top is the flattened crescent-shaped panel

C, ornamented by scrolls and dragons and between the dragons by a vase. Above the 20 top of the flattened panel are scrolls or rosettes a.

D is the summer-front, having a central panel b surrounded by ornamental work. The central panel of the summer-front may 25 be ornamented by the representation of the bust of a woman, as shown at d.

What I claim is—

The design for a frame and summer-front, substantially as shown and described. 30

In testimony whereof I affix my signature in presence of two witnesses.
